UNITED STATES PATENT OFFICE.

WILLIAM C. BENKERT, OF PHILADELPHIA, PENNSYLVANIA.

DESIGN FOR A SHOE-UPPER BLANK.

SPECIFICATION forming part of Design No. 29,202, dated August 9, 1898.

Application filed March 28, 1898. Serial No. 675,507. Term of patent 7 years.

To all whom it may concern:

Be it known that I, WILLIAM C. BENKERT, of Philadelphia, State of Pennsylvania, have invented a certain new and useful Design for 5 Shoe-Upper Blanks, of which the following specification is a true and exact description, due reference being had to the accompanying drawing.

My invention specially relates to the upper-blank used in that class of shoes where the tongue is sewed along each edge, either running all the way or only part of the way to the top of the shoe, it being folded beneath the outside or top when the shoe is laced.

15 Referring to the drawing, which represents an upper-blank embodying my invention, A

is the horseshoe-shaped body of the blank, having the central front portion and two rearwardly-extending side portions. It also has attached at the point E and lying between 20 the two side portions the central tongue D.

Having thus described my invention, what I claim, and desire to protect by Letters Patent, is—

The design for a shoe-upper blank substantially as herein shown and described.

In testimony whereof I have affixed my signature in presence of two witnesses.

WILLIAM C. BENKERT.
